UNITED STATES PATENT OFFICE.

ALBERT F. JOHNSON AND FRANK B. JOHNSON, OF BROOKLYN, N. Y., ASSIGNEES TO THE JOHNSON MANUFACTURING COMPANY, OF SAME PLACE.

SECRET-PRINTING TELEGRAPH.

SPECIFICATION forming part of Letters Patent No. 253,063, dated January 31, 1882.

Application filed November 8, 1881. (No model.)

To all whom it may concern:

Be it known that we, ALBERT F. JOHNSON and FRANK B. JOHNSON, citizens of the United States, residing in the city of Brooklyn, in the county of Kings and State of New York, have invented new and useful Improvements in Instruments for Receiving and Printing Secret Telegraphic Dispatches; and we hereby declare the following to be a full, clear, and exact description thereof, reference being had to the accompanying drawings, which form a part of this specification.

This invention relates to improvements in mechanism for receiving and printing telegraphic messages in such manner that the contents or purport of the same cannot be ascertained by any person in charge of the receiving-instrument, or who may be watching its movements while the message is being printed; and the said improvements are designed to be used in our improved system of transmitting secret messages by electric-telegraph instruments, (described in the specification of said invention marked A, and filed 25 August 16, 1881,) and to be automatically operated by a suitable transmitting-instrument through the medium of electric impulses sent over ordinary telegraphic line-wires.

The invention consists in a telegraphic receiving-instrument provided with devices, as hereinafter particularly described, for automatically sealing over and upon the message-strip a second strip of paper to conceal the message from view before the same passes from the instrument; also, in improved mechanism for operating the transverse feed of the printing-wheel, as hereinafter particularly described; and it further consists in the novel construction and combination of parts, as hereinafter set forth.

In the accompanying drawings, Figure 1 represents a plan view of the instrument; Fig. 2, a side elevation of the same; Fig. 3, an elevation of the opposite side; Fig. 4, a longitudinal vertical section; Fig. 5, a detached view of the mechanism for effecting the transverse and rotary movements of the printing-wheel; Fig. 6, a plan view of the devices for concealing the message-strip while the message

is being printed thereon; and Figs. 7 and 8, detail views, hereinafter explained.

Similar letters of reference indicate the same parts in all the several figures.

As before mentioned, the instrument is automatically operated by means of a suitable transmitting-instrument at the sending-station, through the medium of electric impulses sent over ordinary telegraphic line-wires, the said wires being connected with ordinary electro-magnets on the instrument herein described. Four of such magnets are employed, as follows, viz: o is a magnet, to the armature of which is attached one end of a lever, 13, to the other end of which is pivoted a pawl, 14, which rotates a ratchet-wheel, 12, secured upon the end of a feed-roller, q' , having bearings in the frame R, and effects the longitudinal movement of the message-strip G' . o' is a magnet, to the armature of which is connected mechanism, hereinafter particularly described, which effects the transverse movements of the printing-wheel. o^2 is a magnet, to the armature of which is pivoted a pawl, which rotates a ratchet-wheel, t^2 , fixed upon the shaft t' , which carries the printing-wheel t , and thus effects the rotary movement of the printing-wheel; and o^3 is a magnet, to the armature of which is attached one end of a pivoted frame, 16, the other end of said frame carrying the platen or impressing-roller u , which latter is thereby raised to bring the message-strip G' in contact with the printing-wheel at each stroke of the said armature.

The message-strip G' is placed upon a reel, R^3 , at the top of the frame, and thence passes over a bar, w^3 , and between the printing-wheel t and impressing-roller u , and from thence between the feed-rollers q' and q^2 . The lower feed-roller, q' , is driven by the ratchet-wheel 12, secured to its end, as above mentioned, and the upper feed-roller, q^2 , is journaled at each end to a spring-arm, 15, secured to the frame R, the said spring-arm imparting sufficient friction to insure the regular rotation of the said roller q^2 . By these means the message-strip G' is moved forward the space between lines of printing thereon by each stroke of the armature of the magnet o . A second strip of

paper, G^2 , of about the same width as the former, is placed upon a reel, R^4 , and its end passed over the feed-roller q^2 and between the latter and the lower feed-roller, q' , so that it is fed forward by the action of said rollers along with the strip G' , and covers the printing upon the latter. A narrow coating or line of mucilage or similar adhesive matter is applied to the edges of the strip G' on that side thereof which is uppermost as it passes through the instrument, and is dried before said strip is placed upon its reel R^3 ; and a cup or fountain, Y , containing water, is secured in a suitable position between the reel R^4 and the feed-rollers, and is provided with suitable devices for conducting a small quantity of water to the edges of the strip G^2 , as it passes over the roller q^2 , to dampen its edges, so that the dampened edges of this strip are pressed against the gummed edges of the strip G' as the two strips pass between the feed-rollers and caused to adhere to the same, thus gumming the strip G^2 over the strip G' and concealing the printing thereon, and the strips thus gummed together then pass out of the instrument, as seen at y , with the printing concealed between them.

Suitable devices may be employed for conveying the water from the fountain Y to the edges of the strip in just sufficient quantity to properly dampen the same—as, for instance, a cord, p , extending from a faucet, r , with which the fountain is provided, to a sponge, s , held in a cup, s' , directly over the upper roller, the ends of the lower surface of said sponge being held in contact with the edges of the strip G^2 , so as to dampen the same as it passes over the roller.

The magnet o^2 and the mechanism connected with its armature, as above described, operate to rotate the printing-wheel t , so as to bring the required letter over the impressing-roller u .

The transverse movements of the printing-wheel are effected by the following-described mechanism, which is connected with and operated by the armature of the magnet o' : a is a ratchet-wheel fixed upon a shaft, b , which has bearings in an arm, c , supported by a standard, d , which said wheel is rotated by a pawl or click, e , attached to the armature of the magnet o' the space of one tooth by each stroke of said armature. At the end of the shaft b is secured a crank-wheel, f , having a pin, f' , near its periphery, to which is pivoted one end of a rod, h , the other end of said rod being pivoted to a swivel on the end of the shaft t' , which carries the printing-wheel t . The said shaft t' slides in its bearings, and therefore each revolution of the crank-wheel f causes the printing-wheel to travel back and forth across the frame R , each stroke of the armature causing it to move so as to leave a space between the letters as they are printed on the strip G' . By these means a positive transverse motion is imparted to the printing-wheel, and it prints as it moves in both directions, so

that one line is printed from left to right and the next line from right to left, as shown in Fig. 7, which represents a plan view of the printed strip. The swivel f' at the end of the shaft t' is for the purpose of allowing the rotary movement of said shaft, and the said shaft slides back and forth through the hub of the wheel t^2 , being provided with a spline or feather to admit of its so doing.

The devices for concealing the message-strip as it receives the printing are as follows: i is a plate secured at one end to the frame 16 , or to the bar upon which the said frame is pivoted, as shown in Figs. 4 and 6, and extending from thence to the feed-rollers over the strip, so as to cover the printing upon said strip as it passes from the printing-wheel to the feed-rollers. That part of the said plate i which is immediately over the impressing-roller u is slotted to permit the strip G' to be brought into contact with the printing-wheel when raised by the frame 16 , so as to receive the impression of the type on said printing-wheel. The edges of this slot are turned downward, as at m , so as to press upon the strip as it passes over the impressing-roller u , and keep it snugly in contact with said roller as the impress is being made; and for the purpose of covering the slot or opening in the plate i we employ a second plate, i' , which is suspended by hangers j from the shaft t' , and moves back and forth therewith, a narrow transverse slot, j' , being provided, as shown in Fig. 8, to permit the under surface of the periphery of the printing-wheel to come in contact with the strip G' . By these means the printing upon the message-strip is effectively hidden from view as it travels between the printing-wheel and the feed-rollers, and the position of the plate i in relation to the impressing-roller insures the proper tension of the strip G' as it passes over said roller, so that a perfect impression is made. i^2 is a plate secured to the frame R to guide the printed strip from the feed-rollers and out of the instrument between said plate and another plate, i^3 , which is riveted to the spring-arms 15.

Suitable springs are provided to retract the armatures and pawls in the usual manner, and set-screws to adjust the throw of the armatures, a particular description of which is not deemed to be necessary, as they are constructed and arranged in the usual manner.

This invention is an improvement on the receiving-machine described in our specification marked C; and we do not in this application claim the general construction of said machine, but confine our claims herein to the second strip of paper, G^2 , and the devices for applying the same, and to the devices for operating the transverse feed of the printing-wheel, as hereinafter specifically claimed.

What we claim as our invention is—

1. The combination of the message-strip G' and second strip of paper, G^2 , the feed-rollers q^2 , q' , operated, as described, by the armature of the magnet o , the impressing-roller u and

- printing-wheel *t*, both constructed to operate, as described, through the medium of electric impulses, and the fountain *Y* and sponges, as and for the purpose set forth.
- 5 2. In combination with the message-strip *G'*, fed longitudinally through the instrument by means of the mechanism described, operated by the armature of the magnet *o*, the printing-wheel *t*, having both a rotary and a transverse movement, and operated by the mechanism connected with the armatures of the magnets *o'* and *o²*, as described, the strip *G²*, the feed-rollers *q'* and *q²*, and the plate *i*, all constructed to operate as described, for the purpose set forth.
- 10 3. In a telegraphic receiving-instrument, the combination, with the magnet *o'* and its armature, of the pawl or click *e*, ratchet-wheel *a*, crank-wheel *f*, rod *h*, and shaft *t'*, carrying the printing-wheel *t*, all arranged and operated substantially as described, for the purpose set forth.

ALBERT F. JOHNSON.
FRANK B. JOHNSON.
